DEVICE FOR SECURING PAPERS AND THE LIKE IN FOLDERS AND FILES

Filed May 28, 1931

UNITED STATES PATENT OFFICE

WALTER LANCELOT MOORE, OF WELLINGTON, NEW ZEALAND

DEVICE FOR SECURING PAPERS AND THE LIKE IN FOLDERS AND FILES

Application filed May 28, 1931, Serial No. 540,760, and in New Zealand January 28, 1930.

This invention relates to means for securing papers and the like in folders and files, and provides for the aforesaid purpose an improved device which is simple, cheaply produced, easily operated, and which when closed keeps the papers and the like firmly together, and when opened loosens them sufficiently to allow said papers or the like to be completely opened out without being unfastened, besides which said papers are enabled to be added to or removed from the folder or file with little trouble.

According to the invention the improved device comprises a member formed to lie flat on the papers, and having an edge containing one or more inwardly set portions adapted to bear against cord sections where they emerge from the papers, said cord sections being attached to a backing, and being maintained under tension by outwardly spring pressed grips in which said cord sections are secured towards their free ends.

In order, however, that the invention may be better understood, it will be more particularly described in conjunction with the accompanying drawings wherein

Fig. 1 is a plan view, and

Fig. 2 an elevation showing papers attached to a backing by securing means incorporating the improved device, while

Figs. 3 and 4 are cross sectional views showing the device in positions between the full cord tensioning, and cord slackening positions, and

Figs. 5, 6 and 7 illustrate modifications.

In its preferred and simplest form, the device comprises a piece of springy wire 1 curved or bent near its ends to provide bows with return portions 2 at a distance from the main portion of the wire, the ends of the wire being doubled close against the returned portions 2 and being directed towards the ends of the device, or being bent to form grips 3 for gripping the sections 4 of the cord 4' near their loose ends. The back edge or main portion of the spring wire device 1 thus formed is set or bent inwards as at 5, Fig. 5, or is indented as at 6, Fig. 1, to provide a number of inwardly set portions.

In order to use the wire 1, the papers 7

to be secured are provided with spaced holes 8, through which are passed the sections 4 of a cord which is attached to or passed through a folder or file 9 which constitutes a backing or base. The device 1 is laid on top of the papers 7 with the indentations 6 or inwardly set portion 5 against the cord sections 4 where they emerge from the holes 8 in the papers 7. One cord section 4 is passed over the device 1 so as to bear against an indentation 6 or against the inwardly bent portion 5 and is secured in one of the grips 3 on a returned portion 2 of the device, the other cord section 4 being pulled upon to draw the cord tight against the spring action of the bow and said returned portion 2 carrying the grip 3, following which said other cord section 4 is passed over the device 1 to bear against another indentation 6 or the inwardly bent portion 5, and is finally secured in the grip 3 on the other returned portion 2.

The springs comprised in the bow portions 2 of the device maintain the cord 4' tight, and the pressure of the latter against the indentations 6 or portion 5, which act as levers with the back edge of the wire containing same as a fulcrum, holds the wire flat and tightly against the papers and prevents it from turning over.

In order to loosen the securing means without unfastening same, the spring wire device 1 is raised on its back edge containing the indentations 6 or portion 5 (Fig. 3) following which said back edge is moved in the direction indicated in Fig. 4. During the first of said operations the back edge containing the indentations 6 or portion 5, serves as a fulcrum and the bow portions 2 of the device are compressed further allowing enough of the cord to slide over the indentations 6 or portion 5 to permit the device to be further turned over on the edge carrying the grips 3 and the entire wire 1 to finally come to the position shown dotted in Fig. 1, in which position additional lengths 4a of cord, each equal approximately to the distance between indentations 6 or portion 5 and grips 3, are usable for the papers 7 to slide upon, so as to give a free and flexible

hinge which enables said papers to be turned over easily and be opened out flat.

To close up the folder or file, it is only necessary to place the back edge containing the indentations 6 or portion 5 against the cord sections 4 where they emerge from the papers 7 and turn the device over on said edge back onto the papers, when it snaps down flat on the latter against the action of the 10 spring bow portions 2 and indentations 6 or portion 5, at the same time drawing the cord sections tight or taking up all slack therein, thereby again securing the papers tightly against the backing.

15 To enable papers or the like to be added to or removed from the folder or file, it is only necessary to release the ends of the cord sections 4 from the grips 3 on the device in which they are held.

20 In the forms of the device illustrated in Figs. 6 and 7, the main member consists of a section 10 of rigid sheet material, the back edge of which contains one or a plurality of inwardly offset portions 11 which are the 25 equivalents of the portion 5 or the indentations 6 of the forms illustrated in Figs. 1 to 5, the spring grips 3 in the forms shown in Figs. 6 and 7 being formed on a member 12 preferably of wire attached to the sheet material member, by any suitable means, and formed so that said grips 3 are opposite and normally tend to spring away from the back edge.

30 These last described forms of the device are used and operate in a similar manner to the forms previously described.

What I do claim and desire to secure by Letters Patent of the United States of America is:—

40 1. A device for securing papers and the like in folders and files comprising a backing, a cord, a member having spring means and formed to lie flat upon the papers and having an edge containing indented portions 45 adapted to bear against the sections of said cord where they emerge from the papers, spring grips upon said spring means, said cord being attached to said backing and being maintained under tension by said spring means and said sections of said cord being secured adjacent their free ends by said grips.

50 2. A device for securing papers and the like in folders and files as set forth in claim 1 wherein the spring means of said member having an edge containing the indented portions comprise spring ends spaced from said edge and said spring grips are positioned upon said ends.

55 3. A device for securing papers and the like in folders and files as set forth in claim 1 wherein the spring means of said member having an edge containing the indented portions comprise spring ends spaced from said edge, said ends being turned outwardly so as 60 to form said grips for the sections of said

cords at the inner ends of the turned portions.

4. A device for securing papers and the like in folders and files as set forth in claim 1 wherein said member with the edge containing the indented portions is formed of wire, the ends of said wire being bent so as to form spring bow portions extending away from said edge and the extreme ends of said wire being bent back upon said wire so as 75 to form said grips.

5. A device for securing papers and the like in folders and files as set forth in claim 1 wherein said member is formed of wire and the extreme ends thereof are doubled 80 upon themselves so as to form said spring grips.

6. A device for securing papers and the like in folders and files as set forth in claim 1 wherein said member having the edge containing the indented portions is formed of rigid sheet material and resilient members are attached to said rigid sheet material spaced from said edge and said spring grips are provided upon said resilient members.

7. A device for securing papers and the like in folders and files comprising a backing, a cord having a plurality of sections, a member having spring means and formed to lie flat upon the papers and having an edge containing an indented portion adapted to bear against one of said sections of said cord where it emerges from the papers, grips upon said spring means, said cord being attached to said backing and being maintained under tension by said spring means to which said sections are secured adjacent their free ends by said grips.

In testimony whereof I have signed my name to this specification.

WALTER LANCELOT MOORE.
